UNITED STATES PATENT OFFICE.

CHRISTIAN N. SMITH, OF ELGIN, ILLINOIS, ASSIGNOR OF ONE-HALF TO WILLIAM P. TOPPING, OF ELGIN, ILLINOIS; ALICE MINNIE SMITH AND LILY IRENE SMITH EXECUTRICES OF SAID CHRISTIAN N. SMITH, DECEASED.

MACHINE FOR HEATING AND BENDING METALLIC PRINTING PLATES, SUCH AS ELECTROTYPE AND STEREOTYPE PLATES.

Application filed May 5, 1924. Serial No. 711,298.

This invention relates to that class of machines for heating and bending metallic printing plates, by means of which metallic printing plates, such as electrotype and stereotype plates, or similar plates, may be heated and bent into curved form suitable for use in printing.

The principal object of the invention is to provide a simple, economical and efficient machine for heating and bending metallic printing plates, such, for example, as electrotype and stereotype plates, and the like.

A further object of the invention is to provide an improved machine or apparatus for heating and bending a metallic printing plate together with a filler member formed of compressible sheet material adapted to engage and fill the interstices and depressions in the printing side of such metallic printing plate or plates to be heated and bent, simultaneously and progressively while such filler member and printing plate are in engagement, so as to simultaneously heat and bend the said compressible material and the engaged metallic printing plate, progressively and together, in accordance with this invention or improved method.

Other and further objects of the invention will appear from the following description and claims, and from an inspection of the accompanying drawings which are made a part hereof.

The invention consists in the features, combinations, details of construction and arrangements of parts, and method or mode of operation herein described and claimed.

In the accompanying drawings—

Figure 1 is a view in front elevation partly in central vertical section, of a machine constructed in accordance with my invention;

Fig. 2 is a view in horizontal section taken on line 2—2 of Fig. 1, looking downward and showing a top plan view of the rolls, supporting turntable and of the stationary bed or table upon which the rolls and the means for rotatively supporting the rolls are mounted;

Fig. 3 is a view in transverse vertical section taken on line 3—3 of Fig. 2, looking in the direction indicated by the arrows, and showing mechanism for actuating the rotative support or turntable upon which

the hollow heating roll is supported, including the worm and worm wheel for rotating the turntable, the clutch, and clutch operating and releasing mechanism;

Fig. 4 is a detail plan view of the upper part of the frame in which the upper journal bearings for the rolls are located, including the upper adjustable or sliding journal bearing for the adjustable roll, and the means for removably holding the upper journals of interchangeable hollow heating and bending rolls in operative position;

Fig. 5 is a detail view of a removable journal bearing for an upper journal of a removable hollow heating and bending roll;

Fig. 6 is a detail view in perspective, of a hollow heating and bending roll adapted to be detachably connected with a rotative support or driving means for rotating such roll, and provided with backing sheets and matrix-forming material adapted to pass between the rolls along with the metallic printing plate to be heated and bent, during the operation of heating and bending such printing plate.

In constructing a machine for heating and bending metallic printing plates, such for example, as electrotype and stereotype plates, in accordance with my invention, I provide a frame or stationary bed 1 having supporting legs 2 adapted to support the bed in convenient position. A forwardly projecting front feed table 3 is provided, which is flush with the upper surface of the stationary bed, and is adapted to engage and support and guide the bottom edges of metallic printing plates as the latter are placed in position to be engaged and operated upon by and to pass between the hollow heating and bending roll and the adjacent or auxiliary roll or rolls in the process of heating and bending the printing plates.

Rotatively mounted in a recess 4 in the stationary bed or table 1 and supported by said bed or frame, is a roll-supporting member or turntable 5, which is by preference, circular and so mounted that its upper flat roll-engaging and supporting surface 6 is flush with the top surface of the stationary bed 1 and adapted to rotatively support a hollow heating and bending roll 7, of which

there may be any desired number of different or varying sizes adapted to be used or operated interchangeably upon the same turntable or rotative support 5.

5 The rotative roll-support or turntable 5 is provided with a vertical hollow spindle 8 which extends downward from the center of and is fixed to and may be formed in one integral piece with the turntable. This 10 hollow spindle or shaft 8 is journaled in a suitable bearing 9, which is located at the center of and extends downward from the recessed portion 4 of the stationary bed 1, and is fixed to and rigidly supported by said 15 bed, so as to form a strong and rigid vertical journal bearing adapted to rotatively support the hollow spindle or hollow shaft 8 in upright position, and to support the turntable 5 rotatively in horizontal position 20 with its axis vertical and the top face of the turntable flush with the top surface of the stationary bed 1 and rotative within the recess 4 in the bed.

The journal bearing 9 is attached to the 25 stationary bed or frame 1 by means of an annular flange 10 and bolts 11, which extend through perforations in said flange and are anchored or in threaded engagement with a suitably perforated annular flange 12 30 on or formed integral with a depending bracket or frame portion 13 on or formed integral with the bed 1. (See Fig. 1.)

Driving means is provided for operating or rotating the turntable or rotative roll- 35 support and the hollow heating and bending roll or rolls in the operation of heating and bending metallic printing plates in accordance with my invention.

A very desirable form of driving means 40 for this purpose, is constructed as follows: A worm wheel 14 is fixed to the hollow spindle or shaft 9 by means of a key 15, or other suitable securing means. And a worm or operating screw 16 is rotatively mounted 45 in suitable journal bearings 17, in a depending supporting bracket or frame member 18 on or fixed to the frame 1 in any suitable manner, for example by means of a frame member 19 on the depending frame portion 50 or bracket 13, and securing bolts 20 which extend through suitable perforations in the base of the bracket 18 and are secured in threaded engagement with the frame portion 19. The worm shaft 21, to which the worm 55 16 is fixed by means of a key or other ordinary or suitable securing means, is thus rotatively supported by or journaled in the bearings 17, 17, and also, by preference, in a journal bearing 22, in a bracket or frame 60 member 23, on or forming a part of the frame of the machine. (See Figs. 1 and 3.) And means for driving or connecting the worm shaft 21 with a source of power such as an electric motor or an engine, not shown, 65 is provided.

In the form of the device here shown a driving wheel 24, which may be in the form of an ordinary belt wheel or clutch pulley, is mounted on or adapted to be operatively connected with the worm shaft 21. The 70 driving wheel may be operatively connected with the worm shaft by means of suitable clutch mechanism of any desired ordinary and well known or suitable form; but is, by preference, mounted in normally rotative 75 relation to the worm shaft, and provided with clutch mechanism which is adapted to be operated by a pedal or operating lever mechanism for causing the clutch to connect the driving wheel or pulley with the worm shaft to set the machine in operation or rotate the worm and worm wheel and thereby the turntable and heating and bending roll or rolls in the operation of heating and bending a metallic printing plate or plates. 80 And the clutch mechanism is, by preference, adapted to be automatically disconnected or thrown out of clutch, so as to disconnect the driving wheel and worm shaft, to 85 permit the heating and bending roll, and the worm and worm wheel mechanism and turntable to stop when desired, and yet permit the driving wheel to continue to rotate and to be connected with and disconnected from the worm shaft or driving mechanism for 90 rotating the turntable and heating and bending roll.

For example, a clutch, or clutch and clutch-operating mechanism may be provided and employed which comprises a clutch collar 25 mounted on and fixed to the worm shaft 21 by means of a tapered pin 26, or other suitable securing means, said clutch collar having an annular peripheral slot 27 encircling the collar between an annular end flange 28, and the annular or cylindrical main body portion of the clutch collar; and said clutch collar having the usual longitudinally movable clutch pin mechanism slidably mounted in the clutch collar in parallel relation to the axis of the collar and worm shaft, and adapted to be moved into and out of clutching engagement with the hub of the clutch pulley 24, so as to detachably connect the said pulley 110 with the worm shaft and disconnect said clutch pulley and shaft, as desired or required.

As clutches suitable for this purpose are well known to those skilled in the art, including clutches having clutch pin mechanism spring-pressed in one direction longitudinally of the clutch and of the axis of the clutch and shaft and adapted to be moved into and out of a suitably perforated hub or clutch member on or forming a part of the clutch pulley or driving wheel, such as the wheel 24—such for example as the peripherally notched clutch pin 29 slidably mounted in the collar 25 and adapted to be 115 120 125 130

5 moved into and out of a receiving opening 30 in the hub of the clutch pulley or in the clutch member fixed to the driving wheel, for detachably connecting the wheel 24 in fixed relation to and disconnecting said wheel from the worm shaft, as desired or required, it is believed to be unnecessary and undesirable to describe or illustrate the clutch or clutch mechanism in detail further 10 or otherwise than the same is herein shown and described.

15 The peripherally notched clutch pin 29 is spring-pressed in one direction, that is to say, toward the recessed hub or clutch member 31 fixed to the clutch pulley 24 and provided with the recess 30 for receiving the clutch pin 29; and said pin 29 is provided with an oblique angular shoulder 32 adapted to project into the annular slot 27 20 in the clutch collar, in position to be slidably engaged by the spring-pressed bolt or latch member 33 which is slidably mounted in a recess or socket 34 in the bracket 23, and encircled by a compressible spring 25 35 located in said recess and adapted to tend to press the segmental curved laterally projecting upper end portions of arms 36 into the peripheral slot 27 and in position to engage the shoulder 32 of the clutch pin 29 30 and tend to press said clutch pin away from or out of clutching engagement with the recessed clutch member or hub 31 on or fixed to the clutch pulley 24, when the part 36 of the spring pressed latch member or bolt 33 is 35 in its upper or extended position in the peripheral slot 27, as shown in Fig. 3.

40 A clutch operating pedal 37, having a lever arm 38 is pivotally mounted on the frame of the machine by means of a pivot, rod or similar support 39 which may be of sufficient length to extend from one side to the other of the machine and have its opposite ends supported in the lower portions of a pair of the legs of the machine, as shown in Figs. 1 and 3. The lever arm 38 is connected with the pedal in any desired ordinary and well known or suitable manner, for example, by means of a hollow shaft or sleeve 40 rotatively mounted on the rod 39 45 and fixed to and forming a connection between the lever arm 38 and pedal arm or lever 37. A bell crank 41 is pivotally mounted on a suitable support, which may consist of a rod 42 having its opposite ends supported in corresponding legs of the machine frame. One of the lever arms of the bell crank or lever 41 is connected with the lever 38 of the pedal mechanism, by means of a connecting rod or link 43, or other suitable connecting means; and the other lever arm 44 of the bell crank 41 is connected with the spring-pressed bolt or latch member 33 already described, by means of a connecting rod or link 45, one end of which 50 is connected with the bolt 33 and the other

end of which is connected with the lever arm 44. A flexible connection is thus formed between the spring pressed latch or bolt 33 and the pedal 37 or operating lever arm 38 which may be fixed to or form a part of the pedal or other form of operating lever.

55 An automatic clutch-actuating lever 46 is pivotally mounted on a suitable support, such for example as a bracket arm 47 fixed to the machine frame, and is operatively connected with the clutch mechanism above described, by means of a connecting rod or link 48, the upper end of which is pivotally connected with the lever arm 46 and the lower end of which is connected with the 60 spring-pressed clutch bolt or latch member 33 already described, and also with the adjacent extremity of the connecting rod 45, by means of a connecting pin or bolt 49 or other suitable connecting means. (See Figs. 1 65 and 3.) The lever 46 is thus connected with the clutch mechanism, or with the spring-pressed clutch bolt or latch 33, and with the pedal or clutch-operating lever mechanism including the pedal 37 and lever 38 already described.

70 The automatic clutch-operating or actuating lever 46 has a lever arm 50 which is provided at its outer free end with an anti-friction roll 51 rotatively mounted in and movable with said lever arm. The automatic clutch-actuating lever 46 which also comprises the lever arm 50 is pivotally supported in the bracket 47 by means of a pivot pin or bolt 52, and is operatively connected 75 with the turntable 5 and its hollow vertical spindle 8, by means of an annular cam 53 which is by preference fixed to the worm wheel 14 already described, and encircles the axis of said worm wheel and said spindle. The cam 53 has an upwardly extending annular flange portion 54 which forms the cam proper and has an upper cam face 55 which is adapted to operatively engage the free end of the automatic clutch-actuating lever arm 50 or the anti-friction roller 51 80 on said lever arm, for actuating said lever arm and thereby the spring-pressed clutch bolt 33 or clutch mechanism already described. A depressed or recessed portion 56, which extends part way around the annular cam 53 and is made by cutting away a segment or part of the annular cam flange 55 has its upper face below the level of the uppermost annular cam face portion 55, and is adapted to permit the free end of the lever arm 50 and the anti-friction roller thereon to move downward as the opposite extremity of the lever or lever arm 46 is 85 raised by the upward pressure of the compressible spring 35 of the clutch bolt 33, which spring tends to press the clutch bolt 33 upward into the annular slot or groove 27 in the clutch collar 25, or in an opposite direction from that in which said spring 90

pressed clutch bolt 33 is moved by the pedal 37 and operating lever arm 38 already described.

From the foregoing it will be readily seen that by pressing the pedal 37 downward the spring-pressed clutch bolt or latch member 33 is lowered or withdrawn from the annular peripheral slot 27 of the clutch collar 25, and the lever arm 46 is at the same time lowered, thus causing the actuating lever arm 50 to be raised so that its outer or free end and its anti-friction roller 51 are in the raised position which they will occupy and in which they will be supported by the cam 15 surface 55 when the uppermost part or section of the annular cam surface is in engagement with the anti-friction roller 51, or with the corresponding end of the lever arm 50. The uppermost cam surface 55 of the annular cam 53 will thus support the free end of the lever arm 50 in raised position and tend to press and hold the opposite end of the lever arm 46 and the spring-pressed clutch bolt 33 down against the upward 25 pressure of the compressible spring 35, even after pressure may have been removed from the pedal and from the operating lever 38, thus causing the clutch to engage and operatively connect the clutch pulley in fixed relation to or in operative engagement with the worm shaft, and thereby causing the worm shaft, worm and worm-wheel mechanism, turntable and hollow heating roll on the turntable to rotate during any period of 35 time in which the lever 46 is so operatively engaged and the lever arm 50 so held in raised position by the cam, or by the pedal mechanism, or by both cam and pedal.

From the foregoing it is obvious that 40 pressure on the pedal may be continued for as long a period as may be desired, thereby holding the clutch-actuating lever arm 46 down and the lever arm 50 up or in its raised position independently of the cam or the position of the cam, and even while the depressed portion 56 of the cam is passing beneath the anti-friction roller 51, as well as during any period of time in which the raised or uppermost cam face portion 55 is 45 passing beneath said roller 51 and in position to hold said roller in its raised position in case the pressure on the foot pedal is removed, as it may be at any time. And when the pressure on the pedal is removed the 50 lever arm 50 and roller 51 will be held in raised position only during such period as the upper cam face 55 continues to engage the lever arm 50 or roller 51; and as soon as the upper cam face 55 moves out of engagement with the lever arm 50 and its 55 roller 51, the depressed or lower cam face portion 56 will release and permit the lever arm 50 and roller 51 to move downward as the lever arm 46 is raised by the action of the spring 35 which presses upward on the 60

clutch bolt or latch member 33, thus causing the upper extremity 36 of the clutch bolt or latch member 33 to enter the annular groove 27 in the clutch collar 25 in position to engage the angular shoulder portion 32 of the peripherally notched clutch pin 29 and trip or throw the said clutch pin out of engagement with the recessed clutch member 31 fixed to the clutch pulley, thereby releasing the clutch pulley 24 from the worm shaft and throwing the clutch mechanism out of clutch or to releasing position and permitting the clutch pulley to rotate freely without rotating the worm shaft, the turntable or the heating and bending roll on 70 or connected with the turn table or with which the worm and worm wheel mechanism is connected. The worm shaft 21, thus released, will stop and remain stationary until the clutch is again actuated or thrown into 75 clutching position by the pedal 37, or operating lever 38 or equivalent manually operable means for operating the clutch mechanism, which is accomplished by withdrawing the clutch bolt 33 from the slot 27 or 80 from engagement with the clutch pin which is held out of operative or clutching position by the clutch bolt or latch member 33.

The pedal and clutch-operating lever mechanism and cam or cam and tripping mechanism above described is adapted to actuate or connect and release any ordinary and well known or suitable form of clutch, with only such modifications as will be readily apparent by anyone skilled in the art to 95 which this invention relates; and any ordinary and well known or suitable form of clutch adapted to enable the driving wheel or clutch pulley to be connected with and disconnected from the worm shaft or driving mechanism in an efficient manner is contemplated and may be used, although I prefer the clutch mechanism or clutch operating and releasing mechanism above described which has been found in practice to be very 100 satisfactory and efficient.

Suitable means for operating or releasing the clutch in case of emergency is also provided, which may be of any ordinary and well known form of emergency clutch releasing or other safety device. For example, any ordinary and well known or suitable means for quickly throwing the belt 57 off the driving wheel or pulley 24, in case of emergency or for any reason, may be employed. And as such safety or emergency releasing devices, and devices for stopping the operation of moving parts of a machine of this kind or similar machines are well known and in common use it is not deemed 115 necessary or desirable to describe or illustrate the same in detail herein.

An oil reservoir and gear guard 58 is mounted on a suitable support, such, for example, as a supporting collar 59, and ex- 120 125 130

tends beneath and surrounds the worm and worm wheel. An annular inner flange 60 encircles the hollow spindle 8 and the hub of the worm wheel, so as to retain oil in 5 the reservoir and enable the worm and worm wheel to be run in oil if desired.

Upright frame members or standards 61, 62 are fixed to the stationary frame or bed 1 by bolts 63 or other suitable securing 10 means. And a top frame member 64 extends over the bed from side to side of the bed or machine frame, and has its opposite ends rigidly connected with the corresponding upper ends of the standards 61, 62 and 15 held rigidly in place thereby.

A hollow heating and bending roll 7, already mentioned, having a cylindrical peripheral wall 65, a bottom cylinder head or end wall 66, and an upper or removable 20 head or end wall 67, all forming an inner heating or combustion chamber 68, and provided with a gas burner 69 having a multiplicity of perforations 70, leading from a 25 gas or fluid fuel chamber 71 formed by and between the burner plate 69 and the bottom cylinder head 66, is removably mounted on and detachably connected with and in fixed 30 relation to the rotative roll support or turntable 5. The bottom cylinder head or end 35 wall 66 has a central axial opening 72 which encircles and fits the upright annular flange or rim 73 on or forming an integral part of the turntable 5. And a key or equivalent or other similar securing means 74 is 40 secured in fixed relation to the turntable 5 and its flange 73 and to the bottom cylinder head 66, which is provided with an inner 45 peripheral notch for receiving said key or fastening means. The hollow heating and bending roll 7, or any desired number of 50 such rolls of different diameters or sizes successively—is thus detachably secured to and removably and interchangeably supported by and connected and adapted to rotate with the turntable 5. Rolls of different 55 or various sizes may thus be used successively and interchangeably, and may be successively attached to and disconnected 60 from the turntable and removed and replaced in any desired order interchangeably 65 without disturbing or removing the turntable or the driving mechanism or worm and worm wheel mechanism, or any of the means for rotating the hollow heating and bending roll or rolls.

The upright hollow spindle 8 forms an axial passage through the worm wheel and turntable into the burner and combustion or heating chamber in the inside of the hollow 70 heating and bending roll. And the passage thus formed is adapted to admit fluid fuel to the interior of any desired number of interchangeable hollow heating and bending rolls successively in any desired order, and 75 to the burner or burners of such roll or rolls.

And a gas or fluid fuel supply pipe 75 which communicates with a source of fuel or gas supply, may be mounted in or extend loosely into the hollow spindle 8 which leads to or 80 communicates with the interior of the burner 70 69 or burner chamber 71 mounted on the turntable. And each hollow heating bending roll 7 is provided with suitable air inlet openings 76 and outlet openings 77 for 85 permitting the escape of air or products of combustion from the combustion or heating chamber 68.

The upper end wall or cylinder head 67 is removably secured in place by means of bolts 78 anchored in threaded perforated 80 bosses 79 in the end of the roll; and an inner flange 80 or similar annular shoulder or flange engages and serves to hold the peripheral margin of the removable cylinder head accurately in its proper position in the 85 end of the roll. A stub shaft, axle or journal 81 is fixed to and extends upward from the axial center of each roll 7, and is provided with a loop or eye 82, for receiving a hook or cable end of a block and tackle 90 or other lifting means, for lifting and handling the roll in the operation of placing it on the turntable or removing it therefrom.

The upper frame member 64 is provided 95 with an opening or bearing box 83 which is by preference flanged and angular, and adapted to receive a removable support in operative position a journal bearing member 84 which encircles and is adapted 100 to rotatively support the axle or journal 81 in operative position. And a retaining block or bar 85 having an inner shouldered portion 86 adapted to extend into the angular opening 83 is removably secured to the 105 wall of said opening by means of headed screws 87, or other suitable securing means.

Anti-friction rollers or wheels 88 having upright eccentric axles or journals 89 are 110 rotatively mounted adjacent to the peripheral margin of the recess or opening 4 in the stationary bed 1, and in engagement with the adjacent peripheral margin of the turntable 5, and are adapted to resist side pressure against the roll supported by the turntable by resisting side pressure of the turntable which may result from pressure against the hollow heating and bending roll 115 when in operation in heating and bending a metallic printing plate.

An auxiliary bending roll 90 having an upright axle 91 is rotatively mounted adjacent to and has its axis parallel with the vertical axis of the hollow heating and bending roll 7 on and rotatable with the 125 turntable 5. The roll 90 has its lower axle end or journal 92 rotatively mounted in a sliding or adjustable bearing block 93, which is slidably supported in an elongated opening 94 in the stationary bed 1, and adapted 130

to be moved or adjusted to any desired predetermined adjusted position in said opening, or toward or away from the adjacent roll 7 and turntable 5.

The other or upper end journal 95 of the roll 90 is rotatively mounted or journaled in a similar sliding bearing block 96 which is slidably mounted in and adjustable in a similar manner in an upper elongated opening 97 in the upper frame member 64. The roll 90, with its adjustable journals and journal boxes or supports is thus adapted to be moved toward and from the adjacent roll 7 and the turntable 5, to different predetermined adjusted positions. And the same roll 90 is thus adapted to coact with different hollow heating rolls 7 of different or varying sizes, used successively and interchangeably upon the turntable and adapted to admit a metallic printing plate or plates between the rolls in the process or operation of heating and bending such printing plate or plates.

Suitable means is provided for adjusting and securely holding the roll 90 in any desired predetermined adjusted position with respect to the adjacent hollow heating roll 7 and turntable: For example, each of the sliding journal bearings or bearing blocks 93, 96, is provided with a headed and screw-threaded adjusting screw 97. Each of these adjusting screws has its head rotatively mounted in a suitable opening or slot 98 in the corresponding sliding bearing block. And each of said screws extends through and is in screw-threaded engagement with suitable screw-threaded openings 99 in the frame of the machine, for example, in the upper frame member 64 and bed 1 respectively. (See Fig. 1.)

An upright adjusting-screw-operating shaft 100, is rotatively mounted in suitable bearings 101, 101 in the machine frame; and bevel gear wheels 102, 102 are fixed to opposite ends of said shaft.

Each adjusting screw 97, 97, is provided with a similar bevel gear wheel 103 mounted thereon and rotative therewith, and each in threaded engagement with an adjacent corresponding bevel gear wheel 102 on the shaft 100. Each gear wheel 103 is operatively connected with its corresponding screw 97 by means of a feather or spline 104 fixed to such gear wheel and slidably mounted in and movable longitudinally of a longitudinal peripheral slot 105 in such adjusting screw. Each gear wheel 103 is thus adapted to permit the corresponding adjusting screw 97 to move longitudinally as such screw is rotated with and by means of its gear wheel 103. And each adjusting screw thus rotated, being in threaded engagement with its threaded supporting openings 97, causes a corresponding sliding bearing block 93, 96 to move with such adjusting screw toward

or from the adjacent roll 7 and the turntable, according to the direction of rotation of the adjusting screw or screws, both of which are thus rotated in unison. Suitable operating means such as a hand wheel 106 is provided, for rotating the shaft 100, to actuate the adjusting screws 97 and thereby adjust the roll 90 toward or from the roll 7 as desired.

The hollow heating and bending roll is provided with a peripheral printing-plate-engaging bar 107 which extends longitudinally of the roll and, by preference, from end to end thereof, and in parallel relation to the axis of the roll.

This plate-holding strip 107 is provided with a side flange 108 which projects over a corresponding inner longitudinal marginal notch or recess 109, which is adapted to receive and removably hold in position the corresponding adjacent marginal portion or edge of a metallic printing plate, such as an electrotype or stereotype plate 110 to be heated and bent. The marginal flange 108 projects over the adjacent marginal portion of the metallic printing plate and acts to removably but firmly hold said margin between the flange and the adjacent peripheral surface of the roll 7 during the operation of heating and bending the plate. An outer flexible backing sheet or plate 111, which is by preference, made of flexible sheet metal, extends over the outside of the plate-holding bar 107 and from end to end of said bar, and has its forward edge secured to the peripheral surface of the heating and bending roll 7, or in engagement with the bar 107 and roll, in advance of the said bar, by suitable securing means, such, for example, as a securing strip 112 riveted in place or otherwise secured to the backing plate 111 and its support.

The flexible outer backing plate or sheet 111 is of sufficient length to cover all of the other sheets including the metallic printing plate 110, and may approximately encircle the heating and bending roll 7. A similar inner flexible metallic backing sheet 113 is mounted intermediate the outer flexible backing sheet 111 and the metallic printing plate to be bent, and is between the outer backing sheet 111 and the periphery of the heating and bending roll, in position to extend outside the metallic printing plate during the operation of heating and bending the same. And an intermediate sheet of relatively thick compressible elastic or rubbery material 114 is mounted between the metallic backing sheets 111, 113, and is adapted to yieldingly resist pressure applied to the outer side of the outer metallic backing sheet 111, and to permit the metallic sheets 111, 113 to be pressed inward toward the metallic printing plate during the operation of heating and bending the same. The elastic

sheet 114, however, acts to hold said metallic plates 111, 113 in yielding relation to each other and spaced apart. And the said metallic plates 111, 113 act to prevent the rubbery elastic cushioning sheet 114 from "crawling" and from spreading in direct contact with the sheet or compressible material interposed between the outer backing sheets 111, 113, 114, and the metallic printing plate. In short, the sheets 111, 113, 114 may be said to form an armored backing or laminated plate or set of backing sheets which have the quality of being compressible without causing or permitting either of the outer layers thereof to spread or crawl in the operation of heating and bending a metallic printing plate. The cushioning sheet 114 may be approximately half an inch in thickness, more or less, and is adapted to be compressed between the metallic sheets 111, 113, and thereby much thinner and more dense than when in normal condition and without injury to the compressible sheet. A sheet or sheets of compressible material should be placed between the printing surface of the printing plate and the metallic sheet material or armored compressible and elastic backing material or sheets above described. For this purpose I prefer to employ a sheet or sheets of paper pulp 115 which is spread or laid in contact with and covering the printing side and entire printing surface of the metallic printing plate to be heated and bent. A sheet of wool felt or similar compressible material 116 is laid over the sheet 115; and a flexible sheet of hard rubber or similar material 117 harder than sheet 116 but softer and more readily flexed than the metallic sheets, is interposed between the metallic sheet 113 and the compressible sheet 116 which may be of dry wool felt or blotting paper.

In operation, a metallic printing plate, such as an electrotype or stereotype plate, or printing plate of any desired metallic material is provided and covered with a layer, sheet or sheets of paper pulp or similar compressible material 115.

The sheet 115 is covered with a sheet of suitable compressible material 116, such as wool felt already described, which may be in a dry condition. A flexible sheet 117 of flexible hard rubber, rubber composition or similar flexible material is laid on the sheet 116. A sheet of metal 113 is laid on the sheet 117; and a cushioning sheet of compressible material 114 already described, is laid on the metallic backing sheet 113 and between said sheet 113 and the outer metallic backing sheet 111; and the whole of said elements are placed in position to pass between the heating and bending rolls 7, 90, with the edge of the metallic printing plate in the slot or notch and between the

flange on the plate-holder bar 107 and the periphery of the hollow heating and bending roll, and with the printing plate in contact with the periphery of said heating and bending roll, and the outer backing sheet 111 in position to cover all of said sheets.

The heating and bending roll 7 is heated to the desired temperature suitable to enable the metallic printing plate to be uniformly bent to the required curvature while heated. The rolls are then rotated slowly so as to cause the metallic printing plate, the outer backing sheet and the intermediate sheet material to be passed between the rolls and compressed together and bent. The curved metallic printing plate is then removed from the heating and bending roll.

The operation is repeated in the heating and bending of other similar metallic printing plates, as desired, using the same hollow heating and bending roll for as many plates successively as may be desired, or using heating and bending rolls of different diameters or sizes, interchangeably as desired, and without changing the driving gear or worm and worm wheel mechanism, or disturbing or removing the driving mechanism from its support.

The hollow heating and bending roll or rolls may be either cylindrical or partly flat, or segmental.

I have found in practice that in order to obtain the best and most satisfactory results the hollow heating and bending roll or rolls should be heated to a very high temperature, such as is not readily obtainable by other means than that of a gas burner adapted to heat the inside of the roll and by preference located inside of the roll to be heated.

The hollow roll 7 is provided with an inner annular drum or cylindrical inner wall 118 the lower end of which rests on the burner plate 69, and the upper end of which fits over or in snug fitting engagement with an annular flange portion 119 in the upper end wall 67, thus forming an annular heating or combustion chamber 68 into which the openings 70 in the burner plate 69 lead from the gas or fuel receiving chamber 71.

A concave burner cap 120 in the form of an inverted bowl or cup is mounted at the lower end of the hollow spindle 8, and by preference detachably connected therewith by screw threads or other suitable connecting means; and an air inlet space is provided which leads into the fuel passage formed by the hollow spindle or tube 8 into the lower end of which the upper end of the fuel supply pipe 75 extends loosely in the form of a nozzle, thus forming a burner of the type 125 commonly known as a Bunsen burner, which in the form here shown and described comprises the cup 120, supply pipe or nozzle 75, hollow rotative shaft or spindle 8, burner plate 69 and chamber 71. It is obvious that 130

a separate or additional stationary pipe may be inserted into the rotative hollow spindle 8 in position to encircle the upper end of the pipe 75, if desired, to form a burner of the type known as a Bunsen burner, having the usual cup 120, and air inlet leading into the passage encircled by the cup and into which the nozzle or end of the pipe 75 loosely extends. And a valve 121 serves as a means for controlling the supply of gas or hydro-carbon fuel admitted to the burner. The advantages which result from the use of a burner constructed as herein described and shown will be readily understood by those skilled in the art.

I claim:

1. In a machine for heating and bending metallic printing plates, the combination of a hollow heating and bending roll adapted to rotate upon a vertical axis, rotative supporting and driving mechanism in supporting engagement with said roll, supporting bearings for said driving mechanism, means for connecting said roll with the supporting and driving mechanism, a burner located inside of and adapted to rotate with the roll, and a fuel-supply conduit extending upward through the axial center of said rotative supporting and driving mechanism and adapted to communicate with said rotative burner for supplying fuel to said burner.

2. In a machine for heating and bending metallic printing plates, the combination of a hollow heating and bending roll forming an inner heating chamber having air inlet and outlet openings, a burner member located inside of and adapted to rotate with the roll, rotative supporting and driving mechanism in supporting engagement with said roll, means for connecting said roll with said supporting and driving mechanism, and means on said rotative supporting and driving mechanism and adapted to be detachably connected with said rotative burner for supplying fuel to said burner member for heating the roll.

3. In a machine for heating and bending metallic printing plates, the combination of a hollow heating and bending roll forming a combustion chamber having inlet and outlet openings for admitting air and permitting the escape of products of combustion from the combustion chamber, a burner member located inside of and adapted to rotate with the roll, rotative supporting and driving mechanism in supporting engagement with the roll, means for detachably connecting the roll with said supporting and driving mechanism, and means for supplying fuel to said burner member, for heating the roll, said means comprising a fuel-supply conduit extending upward through said rotative supporting and driving mechanism and communicating with the interior of said burner member and having an air

and gas receiving opening in the lower extremity of said conduit, and means for introducing a supply of gas into said opening.

4. In a machine for heating and bending metallic printing plates, the combination of a hollow heating and bending roll having a curved peripheral wall and end walls forming an inner combustion chamber, and provided with air inlet and outlet openings communicating with the interior of the roll, a burner comprising a perforated burner member located inside of and adapted to rotate with the roll and forming a fuel-receiving chamber inside of the roll, rotative supporting and driving mechanism comprising a roll-supporting turntable, supporting bearings for said driving mechanism, means for operatively connecting said driving mechanism with the roll, and means extending upward through the axial center of said roll-supporting turntable and communicating with the interior of the fuel-receiving chamber formed by said burner member for introducing fuel into said fuel-receiving chamber.

5. In a machine for heating and bending metallic printing plates, the combination of a hollow heating and bending roll having a curved peripheral wall and end walls and provided with an inner combustion chamber having inlet and outlet openings for admitting air and permitting the escape of products of combustion from the combustion chamber, a burner comprising a perforated burner member located inside of and adapted to rotate with the roll and forming a fuel-receiving chamber between said burner member and the adjacent bottom end wall of the roll, rotative driving mechanism supporting bearings for said driving mechanism, means for operatively connecting said driving mechanism with the roll, and means for introducing fuel into said fuel-receiving chamber.

6. In a machine for heating and bending metallic printing plates, the combination of a hollow heating and bending roll forming an inner combustion chamber having air inlet and gas-outlet openings, a perforated burner member located inside of the roll and forming a gas-containing chamber between said perforated burner member and the bottom end wall of the roll, a hollow inner drum extending upward from the perforated burner member and forming an annular peripheral heating chamber between said drum and the peripheral wall of the roll, a rotative roll-supporting member or turntable having an axial opening adapted to permit the introduction of fuel to the burner, supporting bearings for said turntable, means for detachably connecting said roll in operative engagement with said rotative roll-support, and driving mechanism operatively connected with the rotative roll-supporting

member, for rotating the same and thereby said roll.

7. In a machine for heating and bending metallic printing plates, the combination of a hollow heating and bending roll forming an inner combustion chamber having air inlet and outlet openings, a burner member located inside of and adapted to rotate with the roll, a rotative roll-supporting member or turntable having a hollow vertical spindle adapted to permit the introduction of fuel through the hollow spindle and turntable to the burner, said spindle forming a rotative fuel-supply conduit having a gas and air receiving opening in the lower end of said conduit, a stationary gas-supply pipe adapted to discharge a supply of gas into said opening in the rotative conduit, means for operatively connecting the roll with said rotative roll-supporting member or turntable, and driving mechanism operatively connected with the rotative roll-supporting member or turntable for rotating the same and said roll.

23 8. In a machine for heating and bending metallic printing plates, the combination of a hollow heating and bending roll forming an inner combustion chamber having inlet and outlet openings, a perforated burner member located inside of the roll and forming a gas-containing chamber, a hollow drum extending upward from said perforated burner member on the inside of the roll and forming an annular peripheral heating chamber between said drum and the peripheral wall of the roll, a rotative roll-supporting member or turntable having a hollow depending spindle forming a fuel-supply conduit communicating with said burner and having a gas and air receiving opening in the bottom end of said conduit, means for introducing fuel through said hollow spindle to the burner, means for detachably connecting the roll with the said rotative roll-supporting member or turntable, and driving mechanism operatively connected with the rotative roll-supporting member or turntable, for rotating the same and said roll.

9. In a machine for heating and bending metallic printing plates, the combination of a hollow heating and bending roll forming a heating chamber and having a peripheral portion adapted to operatively engage a printing plate to be heated and bent, an outer flexible metallic backing sheet secured to said roll and adapted to extend outside of and over a metallic printing plate to be operated upon, an inner flexible metallic sheet, an intermediate cushioning sheet of compressible elastic material, such for example as compressible rubber, interposed between said flexible metallic sheets, a com-

pressible sheet interposed between the inner flexible metallic sheet and the printing side of the printing plate, means for heating the hollow heating and bending roll, a second roll adapted to operatively engage the outer flexible metallic backing sheet, and means for rotating the hollow heating and bending roll, to simultaneously and progressively bend the compressible sheet and the heated metallic printing plate together.

10. In a machine for heating and bending metallic printing plates, the combination of a hollow heating and bending roll forming a heating chamber and having a peripheral portion adapted to operatively engage a printing plate to be heated and bent, an outer flexible metallic backing sheet adapted to extend outside of such printing plate, an inner flexible metallic sheet over which said outer backing sheet extends, an intermediate cushioning sheet of compressible elastic material interposed between said flexible metallic sheets, a sheet of compressible material, such for example as wood pulp, adapted to engage and fill the interstices and depressions in the printing side of the metallic printing plate, a second roll adapted to operatively engage the outer flexible metallic backing sheet, and driving and heating means adapted to rotate the roll and simultaneously and progressively heat and bend the sheet of compressible filler material and the engaged metallic printing plate together.

11. In a machine for heating and bending metallic printing plates, the combination of a hollow heating and bending roll forming a heating chamber and having a peripheral portion adapted to operatively engage a metallic printing plate to be heated and bent, an outer flexible metallic backing sheet secured to said roll and adapted to extend outside of such printing plate, an inner flexible sheet over which said outer backing sheet extends, an intermediate cushioning sheet of elastic compressible material interposed between said flexible sheets, a sheet of compressible material, adapted to engage the printing side of the metallic printing plate, plate-engaging means on said hollow heating and bending roll for holding the margin of the printing plate in position on the periphery of the said roll, a second roll adapted to operatively engage the outer flexible metallic backing sheet, and driving and heating means adapted to rotate the roll and simultaneously and progressively heat and bend the plate-engaging sheet and metallic printing plate together.

Signed at Chicago, in the county of Cook and State of Illinois, this 21st day of April, 1924.

CHRISTIAN N. SMITH.
